(57) **CLAIM**

The ornamental design for a cutter with pilot tip, as shown and described.

DESCRIPTION

FIG. 1 is a perspective view depicting a cutter with pilot tip of a first embodiment;

FIG. 2 is a front view thereof;

FIG. 3 is a rear view thereof;

FIG. 4 is a side view thereof;

FIG. 5 is an opposite side view thereof;

FIG. 6 is a back end view thereof; and

FIG. 7 is a tip end view thereof.

FIG. 8 is a perspective view depicting a cutter with pilot tip of a second embodiment;

FIG. 9 is a front view thereof;

FIG. 10 is a rear view thereof;

FIG. 11 is a side view thereof;

FIG. 12 is an opposite side view thereof;

FIG. 13 is a back end view thereof; and

FIG. 14 is a tip end view thereof.

FIG. 15 is a perspective view depicting a cutter with pilot tip of a third embodiment;

FIG. 16 is a front view thereof;

FIG. 17 is a rear view thereof;

FIG. 18 is a side view thereof;

FIG. 19 is an opposite side view thereof;

FIG. 20 is a back end view thereof; and

FIG. 21 is a tip end view thereof.

FIG. 22 is a perspective view depicting a cutter with pilot tip of a fourth embodiment;

FIG. 23 is a front view thereof;

FIG. 24 is a rear view thereof;

FIG. 25 is a side view thereof;

FIG. 26 is an opposite side view thereof;

FIG. 27 is a back end view thereof; and,

FIG. 28 is a tip end view thereof.
